PROCESS FOR THE SECRET TRANSMISSION
OF VIBRATED MODULATED CURRENTS

Jean Dieux, Paris, France

Application March 17, 1931, Serial No. 523,224,
and in France May 22, 1930

7 Claims. (Cl. 178—22)

The purpose of the present invention is to effect secret transmission of oscillated, modulated currents free from interference.

More particularly it has for its object the transmission through different media of subsidiary or elementary electric currents resulting from the splitting up of an initial electric current—this transmission being succeeded by a synthesis or recombination of the elementary currents, whereby the original current is restored.

It will be understood that, as the transmission media are different and the subsidiary currents are electrically differentiated, the latter will not be affected by the same interferences at the same time and that the final recombination of the subsidiary elementary currents will restore the initial current, but not the interference effects which neutralize themselves. Moreover, each subsidiary current is only a part of the initial current and if it is intercepted, does not allow of the latter being restored.

The transmission of the elementary, subsidiary currents through different media thus enables the end in view to be attained, that is to say, the secret transmission of an oscillated, modulated current free from interferences.

The present invention relates to a process comprising a transmission of oscillated, modulated currents, effected by the splitting up of these currents, a differentiation of the resulting subsidiary currents, the transmission through various media, the recombination or synthesis of these subsidiary currents, characterized in that the resulting subsidiary currents are differentiated before transmission, by subjecting them to variations of equal amplitudes or intensities but of opposite sign and by recombination of the said subsidiary currents after transmission by subjecting them to variations which are the reverse of those to which they were subjected before transmission.

According to one form of the process, the elements of the oscillated, modulated currents proceeding from an auxiliary source are added to or subtracted from, and after transmission these elementary or subsidiary currents are recombined by adding to them oscillated, modulated currents the reverse of those added before transmission.

According to one method of carrying out the above process use is made, before and after transmission, of one single source or of two identical auxiliary sources of oscillated, modulated currents, the said currents being symmetrically

divided by commutators which are alike except that they act in opposite phase.

According to another arrangement, use is made of two or more amplifiers of different characteristics which differentiate the elementary oscillated, modulated currents by attenuating, augmenting or suppressing certain frequency bands in certain of these currents and by simultaneously augmenting, attenuating or restoring the said frequency bands in others of the said currents.

Arrangements according to the invention are shown by way of example in the accompanying drawings wherein:

Fig. 1 represents a general view of the transmission installation, according to the invention.

Fig. 2 represents a transmission system utilizing intermediary record discs as hereinafter described.

Fig. 3 represents diagrammatically the apparatus employed in the case of transmission by phonographic record discs.

Figs. 4 and 5 are two diagrammatic views of an alternative form of the invention.

The arrangement shown in Fig. 1 comprises an amplifying and analyzing multigate valve L₁ comprising a filament F₁, a grid G₁ and two plates P₁, P₂. The circuit of the vibrated modulated current to be transmitted is connected to the grid G₁ of valve L₁, and this vibrated modulated current thus gives rise to two amplified currents (one in each plate circuit) which can be considered as subsidiary elements of the initial vibrated modulated current. The variation of the characteristics of each plate circuit permits in some manner the control of the division.

Each of these subsidiary elementary currents can be formed either by a single frequency band or by several frequency bands of the initial vibrated modulated current.

Each plate P₁, P₂ is connected to a distinct transmission medium C₁, C₂. Each transmission medium is thus utilized in a continuous manner and always by the same subsidiary element. The two transmission mediums are entirely identical, but distinct from each other. They can be either distant from each other, or near each other. They can, for example, consist of

1. Conductors (transmission by wires)
2. Ether (wireless transmission)
3. Phonograph discs.

The arrangement, according to Fig. 1, also includes an amplifying and synthesizing valve which comprises a filament F₂, two grids G₂ and G_{2'} and a plate P₂.

The grids G_2 and G_2' are respectively connected to transmission mediums C_1 , C_2 , while the plate P_2 is connected to the utilizing circuit.

The vibrated modulated currents arriving at 5 the grids G_2 and G_2' produce in the plate circuit of valve L_2 a single amplified current, which can be considered as the synthetic current of the subsidiary elementary currents.

Thus, after transmission to the valve L_2 the 10 vibrated modulated current which prior to transmission, was divided is reestablished.

The output from valve L_1 is, before transmission, acted upon by a commutator C_1 which sends 15 into the circuits of plates P_1 and P_1' , oscillated, modulated currents, opposite to each other, which superpose themselves, one negatively and the other positively on the elementary or subsidiary oscillated, modulated currents, flowing in the two circuits of the plates P_1 and P_2' . This 20 commutator may be regarded as a double detector which splits up a symmetric, oscillated, modulated current proceeding from a source S_1 and sends into one of the plate circuits the positive part of this current and the corresponding negative part into the other plate circuit.

After transmission and before the recombination of the currents, a commutator C_2 sends into the grid circuits, oscillated, modulated currents, opposed to each other, and the reverse of those 30 added to each circuit before transmission. The commutator C_2 may, for instance, be fed by a source S_2 similar to source S_1 or even by the same source, provided the valves L_1 , L_2 are in proximity to each other, but the commutator C_2 should function in opposite phase to that of 35 commutator C_1 .

The elementary or subsidiary currents are thus restored, after transmission, to their original form.

40. The vibrated or oscillating modulated currents of differentiation can, for instance, be produced by the superposition in one and the same circuit of

45. 1. A vibrated or oscillating current of regular amplitude and frequency coming from a source S_1 S_2 , and

50. 2. A modulating current of well-known characteristics coming from a source T_1 T_2 .

The interferences to which the currents may 55. have been subjected during transmission, have been different for each transmission medium and the final recombination or synthesis either reduces the effects of the interferences or even suppresses them altogether.

55. This purely electrical method of differentiation may be extended to the case where the transmission media are phonograph discs.

In this arrangement there are used, in the case 60. of a duplex transmission, two phonograph discs rotating with the same linear speed, the differentiation being produced not by mechanical action but by an electric effect in the circuits of the recording instruments S_1 , S_2 .

65. The installation in this case, Fig. 2, consists of a valve L_1 similar to that described above, the plates P_1 , P_1' of which are connected respectively to recording instruments S_1 , S_2 , the commutator C_1 producing the differentiation in the circuits of the subsidiary currents. The recorders S_1 , S_2 70. engrave the surfaces of the discs D_1 , D_2 with the same linear speed V_1 .

The recorders S_1 , S_2 are then replaced on the 75. discs D_1 , D_2 by electric pick-ups or reproducers L_1 , L_2 connected to the grids of the valve L_2 , the commutator C_2 acting as in the previously de-

scribed arrangement on the subsidiary currents, before recombination of these currents is effected.

The valve is connected to an output circuit such as the loud-speaker H . $P.$, or to a recording device cutting a final master record.

The intermediary discs D_1 , D_2 are free to rotate throughout the reproducing phase, at a linear speed different from that with which they rotated during the engraving phase, but their respective speeds remain in every case equal to each other at any moment.

A convenient method of driving the discs D_1 , and D_2 is shown diagrammatically in Fig. 3 and consists in supporting the discs on vertical shafts P_1 , P_2 driven from the same driving shaft through the medium of gearing R_1 R_2 , these gears being driven by motor M .

According to a further alternative form of the invention (Fig. 4), the multiplate valve which functions as an amplifier and splits up the initial electric current is replaced by two or more ordinary amplifiers A_1 , A_2 , fed respectively by one or more microphones M_1 , M_2 each circuit A_1 , A_2 thus receiving the differentiated sound elements emitted by source S .

When this arrangement is adopted, it is possible to differentiate the oscillated, modulated currents by combined action on the amplifiers. Thus for example, two amplifiers A_1 , A_2 of different characteristics may be employed, one producing attenuation, augmentation or suppression of certain frequency bands of the oscillated, modulated current traversing the circuit, while in the other, on the contrary, the corresponding frequency bands in the second elementary or subsidiary modulated current may be simultaneously augmented, attenuated or restored.

The elementary currents thus transformed by the amplifiers A_1 , A_2 , act on two recording instruments S_1 , S_2 which engrave the sounds on the discs D_1 , D_2 . These discs D_1 , D_2 then actuate two electric pick-ups or reproducers L_1 , L_2 , which give rise to the separate currents in amplifiers A_3 , A_4 , the recombination of these currents being effected by 115 a single recording instrument S_5 which engraves a single master surface G as indicated diagrammatically in Fig. 5.

What I claim as my invention and desire to 120 secure by Letters Patent is:—

1. The process for the transmission of oscillated, modulated currents, which consists in dividing these currents, differentiating the subsidiary currents so produced, adding to the subsidiary currents elements of oscillated, modulated current 125 proceeding from an auxiliary source, transmitting through different media the differentiated subsidiary currents, adding to each subsidiary current oscillated, modulated currents the reverse of those which were added to them before transmission, and finally, effecting the recombination of the subsidiary currents.

2. The process for the transmission of oscillated, modulated currents, which consists in dividing these currents, differentiating the subsidiary currents so produced, adding to the subsidiary currents elements of oscillated, modulated current 130 obtained by a previous commutation of an auxiliary current, transmitting through different media the differentiated subsidiary currents, adding to each subsidiary current oscillated, modulated currents obtained by the commutation of the auxiliary current, of opposite phase to that obtained from the first commutation and, finally, recombining of the subsidiary currents.

3. In a system for the transmission of oscillated, modulated currents, a valve having several anodes, a grid and filament joined to the circuit producing the current to be transmitted, a second valve having several grids, an anode and filament both connected with the circuit for utilizing the transmitted current, means connecting the anodes of said first valve to the grids of the said second valve, a source of oscillated, modulated current, a commutator symmetrically dividing the oscillated, modulated current from the single source and causing each portion of this current to act upon each of the subsidiary currents before transmission, a second source similar in all respects to said first source and a second commutator similar to said first commutator but functioning in phase opposite to that of the latter and symmetrically dividing the current of said second source, and causing each portion of the current to act upon each of the subsidiary currents after transmission. 80
4. In a system for the transmission of oscillated, modulated currents, a valve having several anodes, the grid and filament both connected to the circuit supplying the current to be transmitted, a second valve having several grids, a plate and a filament both connected with the circuit for utilizing the transmitted current, transmission media consisting of two phonographic discs rotating with the same linear speed, means allowing the subsidiary currents produced by splitting up of the initial current to undergo variations of equal amplitude but of opposite sign before their transmission, and means allowing the subsidiary currents, after transmission, to undergo variations the reverse of those they underwent before transmission. 85
5. The process for the transmission of vibrated, modulated currents, which consists in dividing the vibrated modulated current to be transmitted into several distinct and uninterrupted subsidiary currents, subjecting these vibrated modulated subsidiary currents, prior to transmission, to different variations of frequency and amplitude, transmitting said differentiated subsidiary currents through different media, imparting to said subsidiary currents variations the reverse of those to which they were subjected before transmission and, finally, combining said several reconstituted subsidiary currents. 90
6. The process for the transmission of vibrated modulated currents, which consists in dividing the vibrated modulated current to be transmitted into several distinct and uninterrupted subsidiary currents, differentiating said subsidiary currents by amplifying them with different amplifying intensities and by modifying certain frequency bands, transmitting said differentiated subsidiary currents through different media, subjecting said subsidiary currents after transmission to variations the reverse of those which they were subjected to before transmission by amplification and modification of certain frequency bands, and, finally, combining said various subsidiary currents. 95
7. The process for the transmission of vibrated modulated currents which consists in dividing the vibrated modulated current to be transmitted into several distinct and uninterrupted subsidiary currents, subjecting, prior to transmission, said vibrated modulated subsidiary currents to different variations of frequency and amplitude, transmitting said differentiated subsidiary currents by means of phonograph surfaces, imparting to said subsidiary currents variations the reverse of those to which they were subjected prior to transmission and, finally, recombining said different subsidiary currents. 100
